C. J. PILLIOD

FLUID CONTROL MEANS

Filed June 5, 1920

INVENTOR
Charles J. Pelliott,
By Burnham & Crampton,
His atty.

UNITED STATES PATENT OFFICE.

CHARLES J. PILLIOD, OF TOLEDO, OHIO, ASSIGNOR TO DANIEL SEARLES, TRUSTEE,
OF TOLEDO, OHIO.

FLUID-CONTROL MEANS.

Application filed June 5, 1920. Serial No. 386,849.

To all whom it may concern:

Be it known that I, CHARLES J. PILLIOD, a citizen of the United States, and a resident of Toledo, in the county of Lucas and State of Ohio, have invented a certain new and useful Fluid-Control Means; and I do hereby declare the following to be a full, clear, and exact description of the invention, such as will enable others skilled in the art to 10 which it appertains to make and use the same, reference being had to the accompanying drawings, and to the characters of reference marked thereon, which form a part of this specification.

15 This invention relates to fluid control means for use particularly in connection with furnace door operating mechanisms or the like, and has for its object the provision of a simple, improved and highly efficient 20 apparatus of this character which is quick and practically positive in its operation and adapted to permit a sudden initial movement of the control piston during each stroke thereof and a cushioning of the 25 remaining portion of the piston stroke to enhance the practicability and commercial value of such mechanism.

The invention is fully described in the following specification, and while, in its 30 broader aspect it is capable of embodiment in numerous forms, a preferred embodiment thereof is illustrated in the accompanying drawings, in which,—

Figure 1 is top view of a control means 35 embodying the invention with a part broken away. Fig. 2 is a side elevation thereof with portions broken away. Fig. 3 is a similar fragmentary view thereof with the valve and its enclosing casing removed. Fig. 40 4 is a section on the line 4—4 in Fig. 3 with a portion broken away. Figs. 5 and 6 are diagrammatical views of the valve member at different limits of its movement, and Fig. 7 is an inner side view of the valve member.

45 Referring to the drawings, 1 designates a cylinder having a piston 2 therein with its rod 3 projecting through a stuffing box 4 in an end of the cylinder and, in the present instance, into a cylindrical guide 5 where it connects with a plunger 6 movable therein. A connecting rod 7 pivotally projects from the outer end of the plunger 6 and connects with the mechanism to be operated or con-

trolled in its movements by the control mechanism. The inner end of the chamber 55 formed by the guide 5 is provided with a relief passage 8.

One side of the cylinder wall is provided with a flat circular valve seat 9 having a pair of live steam ports 10, 11 therein in 60 communication through the cylinder walls with respective ends of the cylinder, near the top of the valve seat. At the lower portion of the valve seat, in the present instance, is provided an exhaust port 12, 65 which leads to an exhaust pipe 13 and thence to any suitable point of discharge to the atmosphere. At one side of the port 12 is located an exhaust port 14 and at the other side an exhaust port 15 each being in 70 communication through a wall passage with the interior of the cylinder, the port 14 being open to the cylinder when the piston 2 is at the limit of its right hand stroke and the port 15 being open to the cylinder when the 75 piston is at the limit of its left hand stroke, as indicated in Fig. 1. It is thus evident that when the piston has substantially completed its stroke in either direction one or the other of the exhaust passages 14, 15 will 80 be uncovered at the cylinder end thereof to permit a sudden exhaust therefrom to relieve the pressure at the adjacent end of the piston. These exhaust passages may be termed uniflow exhaust passages. 85

Auxiliary exhaust ports 16 and 17 are provided in the valve seat at opposite sides of its center and have their passages in communication with the respective ends of the cylinder and form auxiliary exhaust 90 passages therefrom. The valve seat is also provided in its face with recesses 18 and 19 extending from the ports 14 and 15 toward the adjacent respective ports 16 and 17 for the purpose hereinafter described. 95

A disk valve 20 is mounted over the valve seat 9 for turning movements thereon and is enclosed by a casing 21, which is fixed to the cylinder in surrounding relation to the valve seat by screws 22, or in any other suitable manner, and cooperates with the valve 20 to form a live steam chamber 23 at the outer side of the valve, which chamber is in communication with a source of fluid pressure supply through a pipe 24. A valve 100 stem 25 projects from the valve 20 without 105

the casing 21 and carries an operating arm 26 at its outer end, which arm is connected by a rod 27 to any suitable manual control. The stem 25, in the present instance, projects through the valve and is centered in a cylindrical socket 28 in the valve seat.

The valve 20 is provided with two ports 29 and 30, the former being adapted to register with the live steam port 10 in the valve seat when the valve is in one position of its movement and the latter with the steam port 11 when the valve is in another position of its movement and thereby open communication between the live steam chamber 23 and one end or the other of the cylinder, depending on the position of the valve. The inner or seat side of the valve 20 is provided at opposite sides of its center with segmental grooves or recesses 31 and 32, respectively, in permanent communication with the auxiliary exhaust ports 16 and 17 in the valve seat. A pair of recesses 33 and 34 are provided in the lower portion of the valve at its inner side in permanent communication, respectively, with the uniflow exhaust ports 14 and 15 and the respective recesses 18 and 19 in the valve seat.

It is evident that when the valve is in the position shown in Fig. 5, the valve port 29 is open to the cylinder passage 10, thereby admitting live steam to the left hand end of the cylinder, and that at the same time both the auxiliary and uniflow exhaust passages 17 and 15 at the opposite end of the cylinder are in communication with the main exhaust passages 12-13 by reason of the recesses 32, 19 and 34 in the valve and seat being in communication and the latter in register with the exhaust passage 12, as shown by dotted lines in Fig. 5. With the valve in this position the exhaust passages 16 and 14 at the left end of the cylinder are closed. Upon a movement of the valve to the left to the position indicated in Fig. 6, the action of admission and exhaust of fluid to and from the cylinder is reversed so that live fluid is admitted to the right end of the cylinder and the exhaust takes place at the left end thereof.

In the use of this control in connection with a furnace door operating mechanism, as shown in my application for United States Letters Patent Serial Number 376,524, filed April 26, 1920, with which it is more particularly intended for use, the valve does not have a neutral position in which both cylinder admission ports are closed, but is intended to normally stand in the position shown in Fig. 5 to admit fluid to the left end of the cylinder and hold the piston at the right end thereof, thereby exerting a door closing pressure on the connected operation mechanism. To effect an opening of the doors the valve is manually

moved to the left to the position shown in Fig. 6 in which live fluid is admitted to the right end of the cylinder to force the piston to the left and exhaust takes place from the left end, first through both the uniflow exhaust passage 14 and the auxiliary exhaust passage 16 and then, after the closing of the passage 14 by the piston, through the auxiliary passage alone. The taking place of the exhaust through the auxiliary passage 16 alone effects a retarding of the exhaust so as to cushion the outer end of the piston stroke and prevent the hammering action which would otherwise take place by reason of a sudden stopping of the piston.

I wish it understood that the invention is not limited to any specific construction, arrangement or form of the parts, as it is capable of numerous modifications and changes without departing from the spirit of the claims.

Having thus described my invention, what I claim as new and desire to secure by Letters Patent, is,

1. In a fluid control, a cylinder, a live fluid chamber having a valve seat, an inlet passage from each end of the cylinder to the valve seat, exhaust passages also leading from each end and from the central portion of the cylinder to the valve seat, and a disk valve mounted on the seat and having a pair of ports for opening communication respectively between the chamber and one or the other of the inlet passages when the valve is in a predetermined position, said valve seat also having a main exhaust passage to the atmosphere, and said valve having a recess in permanent communication with each end exhaust passage and a recess in like communication with the exhaust passage from the central portion of the cylinder, said valve recesses cooperating to place the exhaust passages for either cylinder end in series communication with the main exhaust passage when the inlet passage at the opposite cylinder end is open.

2. In a fluid control, means forming a cylinder, a live fluid chamber, a valve seat therein, an inlet passage extending from the valve seat to each cylinder end, an auxiliary passage extending from the valve seat at opposite sides of its center to each cylinder end, a uniflow exhaust passage extending from the valve seat to each cylinder end with the valve seat end of each passage broadened toward the auxiliary passage which extends to the same cylinder end and a main exhaust passage extending from the valve seat at a point between the uniflow exhaust passages, a disk valve mounted on said seat within the chamber and having a pair of ports therethrough adapted to open communication respectively between the chamber and one or the other of the

inlet passages when the valve is in predetermined position, said valve also having a recess in permanent communication with each auxiliary passage and a recess in permanent communication with each uniflow exhaust passage, said valve recesses cooperating in pairs with the seat recesses to place

the exhaust passages for either cylinder end in series communication with the main exhaust passage when the inlet passage at the other cylinder end is open. 10

In testimony whereof, I have hereunto signed my name to this specification.

CHARLES J. PILLIOD.
